GARMENT SUPPORTING BELT

Filed Oct. 6, 1927

FIG. 1.

Inventor

MARY STARMER

By

Amelior B. Brock

Attorney

UNITED STATES PATENT OFFICE.

MARY STARMER, OF NEWPORT NEWS, VIRGINIA.

GARMENT-SUPPORTING BELT.

Application filed October 6, 1927. Serial No. 224,383.

My invention contemplates an improvement in belts for personal wear by either ladies or gentlemen and contemplates especially a chain holding convenience by means of which the watch chain, or other chain, may be supported or suspended in an attractive and neat manner. The chain holding device is located at the inner side of the belt and therefore does not mar the appearance of the exterior of the belt, and the chain holding device provides a loop through which the watch chain may with facility be passed for the purpose of suspending the chain.

In carrying out my invention, I utilize a tab in connection with the belt, which tab may be formed as an integral part of the belt, or it may be attached to the belt in suitable manner. The tab is provided with a suspending loop or slot for the watch chain and this opening is preferably of sufficient size to permit the spring ring of a chain to pass therethrough, thus permitting the chain to be looped as well as used in single style.

My invention consists in certain novel combinations and arrangements of parts as will hereinafter be more fully described and claimed. In the accompanying drawings, I have illustrated one complete example and a modified form thereof, of the physical embodiment of my invention wherein the parts are combined and arranged according to the best mode I have so far devised for the practical application of the principles of my invention.

Figure 1 is a view showing the inner sides of the two separated ends of a garment supporting belt, the buckle end of the belt being provided with the chain supporting loop of my invention;

Fig. 2 is a view of the buckle supporting end of the belt with the fold flattened out and showing the chain supporting loop or tongue stamped from the belt material;

Fig. 3 is a face view at the inner side of the buckle end of the belt showing a slotted tab riveted to the folded portion of the belt; and

Fig. 4 is a cross sectional detail view at line 4—4 of Fig. 3.

In carrying out my invention, I utilize a belt having the usual buckle end 1 and perforated end 2 and the buckle 3 is shown in Fig. 1 as a standard type of buckle. The belt may be for either men's wear or ladies' wear; and may be fashioned of leather or fabric, or it

may be fashioned from ribbons or other materials that are suitable for the purpose.

The buckle 3 is retained at an end of the belt in usual manner by means of the fold 4 and the material of the fold is bent to form a sleeve as at 5 for the cross bar 6 of the buckle. The usual tongue or prong 7 of the buckle is passed through the slot 8 provided therefore in the belt and the material of the belt is folded on the dotted line 9 indicated in Fig. 2. The fold 4 of the belt may be stitched to the belt as at 10 or secured in any other suitable manner.

In one form of my invention, the device for supporting the chain C is fashioned from the material of the fold 4. In this instance, a U-shaped tongue 11 is cut or stamped out as at 12 from the material of the fold 4 and the U-shaped tongue provides a slot 13 in the body of the belt through which the chain may be passed. The U-shaped tongue or tab may be positioned in any desired angle, as shown in the two angles of Fig. 1 and Fig. 2, and the tongue may be flexed or bent inwardly from the fold 4 to permit ready insertion of the chain through the slot 13 in order that the chain may hang from the U-shaped tab as shown in Fig. 1. The tab is preferably cut out from the fold 4 in order that the appearance of the belt may not be altered and for convenience in suspending the chain beneath the belt and the tab is thus rendered invisible from the exterior of the belt.

In some instances, the tab may be attached to the fold 4 as indicated in Fig. 3 and Fig. 4. In these figures, the tab 14 is provided with a slot 15 and it is secured as by rivets 16 to the fold 4 at the buckle end of the belt. As thus shown, the rivet 16 is not visible from the exterior of the belt, nor is the slotted tab 14 visible. The shape of the slots 13 and 15 of the tabs may be varied for different purposes and the shapes of the U-shaped tab 11 and of the attached tab 14 may also be changed. In some instances, it may be desirable to stitch the tab 14 to the fold of the belt instead of using the rivet or fastener 16.

From this description taken in connection with my drawings, it will be apparent that the chain holding tab may be added to the belt without materially adding to the cost of manufacture of the belt, and the tab may be used or not used as desired, and yet because of its position at the inner side of the belt, it is not visible and does not alter the appear-

ance of the belt. By attaching the tab to the fold 4, or stamping the U-shaped tab from the fold, any weakening of the material of the belt is avoided, and the chain supporting tab is located in convenient and desired position.

Having thus fully described my invention, what I claim as new and desire to secure by Letters Patent is—

1. A garment supporting belt having a

buckle supporting end with an inner fold 10 and a slotted chain supporting tab on said fold.

2. A garment supporting belt having a buckle supporting end with an inner fold and a slotted U-shaped chain supporting tab partially cut from said fold.

MARY STARMER.
